UNITED STATES PATENT OFFICE.

WINFIELD E. MCINTYRE, OF FAYETTEVILLE, NEW YORK.

PAPER-MAKING MACHINE.

Application filed July 24, 1924. Serial No. 727,995.

To all whom it may concern:

Be it known that I, WINFIELD E. MCINTYRE, a citizen of the United States, residing at Fayetteville, in the county of Onondaga and State of New York, have invented certain new and useful Improvements in Paper-Making Machines, of which the following is a specification.

This invention relates to improvements in paper-making machines, particularly of the type employing cylinders for forming tissue and other thin and light papers.

The object of the invention is to provide novel and simple means for regulating the flow of the liquid pulp into the vat that contains the vacuum cylinder upon which the web of paper is formed. A further object is to provide means for agitating and remixing the liquid pulp after it enters the vat and before the web is formed, for the purpose of effecting a more even distribution of the binding fibers throughout the web, thereby equalizing the tensile strength of the web in all directions and obviating the usual streaking and the pronounced longitudinal grain common to the products of the older tissue paper machines. A further object is to provide means for deflecting the liquid pulp from the suction cylinder while the stock is being agitated within the vat, thereby preventing the binding fibers from assuming generally a longitudinal course, which produces the usual one-way grain of the web. A further object is to provide a flow regulator which is interposed between the flow-box and the vat, the said regulator being adjustable towards and away from the cylinder for decreasing and increasing the volume, as well as the agitation of the pulp, the said regulator also controlling the head of the pulp which is being delivered to the vat. A further object is to provide a flexible apron which is supported by the deflector, the said apron being arranged to frictionally engage and shield the portion of the cylinder directly opposite the flow regulator, for preventing direct contact of the pulp with the cylinder adjacent the point where the agitation and remixing of the pulp takes place. A further object is to provide means for drying the newly formed web of paper while it is travelling from the couch-roll to the heated drying rolls, for preventing the breaking of the web; the said preliminary

drying rendering it possible to effect the final drying and curing of the paper by the use of a relatively small number of heated rolls, as well as to operate the machine at higher speeds than heretofore. And a further object is to generally improve and simplify the construction, arrangement and operation of tissue paper making machines.

I attain these objects by the means set forth in the detailed description which follows, and as illustrated by the accompanying drawings, in which—

Figure 1 is a front side elevation of the "wet-end" of a paper making machine, to which my improvements are applied. Fig. 2 is respectively an end and a front face view of the pulp deflector, with the flexible apron attached. Fig. 3 is an enlarged broken side elevation of the machine, in which the vat and neighboring parts are shown in section; the latter being taken on line 3—3 of Fig. 5. Fig. 4 is a plan view of the flow gage. Fig. 5 is a horizontal section, taken substantially on line 5—5 of Fig. 3. And Fig. 6 is a detail view of the lowermost main press-roll, showing means for driving the several rolls and belts throughout the machine.

In the drawings, the frame of the machine which supports all of the working parts, consists of similar side portions 2 and 2', which may rest upon any suitable foundation. 3 represents the substantially semi-circular vat, to which the liquid pulp 4 is supplied by an ordinary flow-box 4'; the vat and the compartment 4' being separated by an upright dam or barrier 5, which extends transversely across the machine. In the vat 3 is disposed the usual vacuum cylinder or mold 6, which is mounted upon a shaft 6', the said parts being rotatable in the vat in the direction of the arrow on the end of the cylinder, by the frictional contact of the usual couch-roll 7. The couch-roll is rigid on a shaft 7', which journals in bearings 7^a, the latter being mounted upon forwardly extending arms 7^b, which are pivoted to frame uprights 2^a (see Figs. 1 and 3). The couch-roll 7 is driven by a felt belt 8, which extends forwardly and passes between main press-rolls 9 and 9'. The felt 8 then extends forwardly again and then downwardly and back to the rear end of the machine, and in doing so it is sup-

ported and guided by a series of idler and tension rolls 10—10', and finally passes between a pair of squeeze rolls 10^a, which are located near the cylinder 6 and the roll 7. 5 The press-roll 9 is rigid on a shaft 9^c, which rotates in half-bearings 9^b, and may be driven by any suitable power by means of miter-gears 9^c—9^d. The press-roll 9' is operated by the roll 9 under varying tension, 10 which is produced by a lever 12 which is pivoted to an upright 2^b of the frame, and by a rod 12' and a lever 12^a, the latter carrying an adjustable weight 12^b for regulating the tension, as shown in Fig. 1. The felt 8 15 is washed and cleansed by a whipper 13, and pipes 13'—13^a which spray the opposite sides of the felt with fresh water before it reaches the squeeze rolls 10^a. The liquid pulp 4 flows from the box 4' over the dam 20 5 into the vat 3 in a continuous stream, and the layer or web of paper is formed on the submerged outer surface of the cylinder 6, which carries the web around to the point of contact with the felt 8. The felt 8 then 25 takes the web from the cylinder 6 and carries it around the couch-roll 7 and thence forwardly to the press-rolls 9—9' in a continuous strip.

14 represents a second relatively long felt 30 belt, which passes between the press-rolls 9—9', over an idler roll 14', and back to the top of the roll 9', from which point said felt extends towards the rear end of the machine, and is supported and guided by 35 a series of idler and tension rolls 15—15', by which it is carried back towards the press-roll 9'. The felt 14 is washed by fresh water spray from a pipe 16 which lies upon the felt, the water being sucked from the 40 felt 14 by a vacuum box 16'. The felt 8 laden with the wet web of paper it receives from the cylinder 6, also passes over a series of suction-boxes 8' (see Figs. 1 and 3), which remove the greater portion of 45 the moisture from the web.

The web of paper while passing between the press-rolls 9—9' is picked up by the felt 14 which carries it around the roll 14', then rearwardly towards the roll 9', where the 50 web is taken from the felt 14 by a plain relatively large press-roll or drum 17, by which the web (shown at 17' in Fig. 1) is delivered to the usual heated driers (not shown). By the disposition and arrangement of the felts 8 and 14, and also the suction-boxes 8' and 16' the web 17' is 55 delivered to the drum 17 in a relatively dry state, which practically obviates all danger of breakage of the web after it leaves the 60 drum 17.

Heretofore, practically all tissue paper made by cylinder machines, has shown a pronounced grain, which runs in the direction of the length of the webs that are 65 formed upon the vacuum cylinders, as 6.

This one-way grain, tends to produce a marked tensile strength longitudinally, but the webs are almost entirely lacking in tensile strength laterally, and often break or slit at the slightest transverse strain. This 70 great variation between the longitudinal and transverse strength of the tissue paper produced by the older cylinder machines is due largely to the age-old method of delivering the liquid pulp to the vats, in which the 75 suction cylinders rotate, in a direct and uncontrolled stream. It has been the practice to flow the liquid pulp over the dam, as 80 5, which separates the box 4' from the vat 3, in such manner that the pulp, upon entering the vat makes direct contact with the cylinder, and as the flow of the pulp towards the constantly rotating cylinder is continuous in the general direction of the length of the web of paper, most of the relatively long 85 binding fibers incorporated in the pulp are carried towards the cylinder and become fixed in the web of paper parallel to each other and with their linear dimension pointing in the direction of the flow of the pulp and the 90 rotation of the cylinder, thereby producing the longitudinal grain referred to, and by reason of the aforesaid free and uncontrolled delivery of the pulp to the vat, comparatively few of the fibers are found disposed 95 transversely in the web, which accounts for the extremely low tensile strength laterally. Furthermore, this quiet and undisturbed flow of the pulp into the vat, allows the 100 fresh stock to mingle with the pulp already 105 in the vat, in such manner that the solid portions of the pulp invariably collect in more or less dense masses, which when drawn against the foraminous surface of the cylinder by the suction tends to form dark and 110 heavy streaks upon a relatively light and thin back-ground, thereby producing an irregularly clouded sheet or web; the said streaks remaining after the paper is dried 115 ready for use. The weakness of the tissue 120 paper made by the older cylinder machines, which split readily when subjected to transverse strains, renders the paper unfit for wrapping and many other uses. The uneven formation or thickness of the paper, due to the aforesaid streaking also interferes with the proper drying and curing of the rapidly moving web and renders the true and smooth winding of the finished product more difficult than if the binding fibers and the 125 short pulp were spread in a manner to eliminate the dense and light streaks, as explained.

The primary object of the present invention is to produce a web or sheet of paper, 125 which has substantially the same strength laterally as longitudinally, and wherein the aforesaid pronounced longitudinal grain of the web is eliminated. By the use of my improvement, the solid particles of the pulp are 130

agitated within the vat before making contact with the cylinder 6, in such manner that both the long fibers and the short pulp are evenly distributed throughout the liquid mass, and the tendency to form alternate dense and light longitudinal streaks in the web of paper is obviated. The present invention enables me to produce a web of paper by a cylinder machine similar to that 10 produced by the well-known Fourdrinier machines, without pronounced grain in any direction, and having substantially equal tensile strength in all directions. The present invention prevents the fibers from 15 taking any general or preferred direction in the web of paper. My improvement consists principally of the following parts:

18 represents a novel flow gage or regulator comprising a flat strip or bar of wood 20 or metal having a length substantially equal to the length of the vat 3 and the dam 5, and which is disposed horizontally upon the top of the dam parallel to the cylinder, as shown in Figs. 1 and 3. The flow gage 18 25 is preferably broader than the top face of the dam, and is adjustable thereon by means of transverse slots 18', through which loop-headed screws 19 are inserted and screwed into the dam. The flow-gage is movable 30 horizontally towards and away from the cylinder 6, for decreasing and increasing the depth or volume of the pulp flowing from the box 4' to the vat 3. 20 represents a stock deflector comprising a relatively thin 35 wood or metal strip, which is disposed at an angle to the part 18 and substantially radial to the axis of cylinder 6, as shown in Figs. 1 and 3, and is preferably positioned slightly above and forwardly of the dam 5. The deflector is held adjustably in place and is 40 guided by spaced cleats 20', which are secured to the opposite ends of the vat 3 (see Figs. 3 and 5), and to its lower edge is secured a flexible apron 20^a (see Figs. 1, 2 and 3), which extends downwardly and 45 partially covers the woven-wire surface of the cylinder 6. The apron 20^a preferably extends a considerable distance below the flow-gage 18, as shown in Figs. 1 and 3, and prevents the pulp which flows over the 50 gage from contacting directly with the said portion of the cylinder. The object of this construction and arrangement of the parts 18, 20 and 20^a is to prevent the fresh pulp 55 from being carried downwardly in an uninterrupted stream by the rotating drum until the inflowing mass has been suitably agitated and remixed, as explained. The agitation and remixing of the fresh pulp 60 occurs mainly beneath the overhanging margin 18^a of the gage, and is effected by the pulp flowing over the gage, thence against the apron 20^a, which being stationary and also bulging towards the ledge 18^a and the 65 dam, causes the pulp to swirl and tumble

beneath the ledge and become thoroughly mixed without interference by the rotating drum 6, until the pulp sinks below the lower margin of the apron. By this time the binding fibers which form an important part of 70 the solids of the pulp become pointed in every direction and are evenly distributed throughout the mass of liquid, and when the mass finally makes contact with the drum 6 and is acted upon by the vacuum 75 which forms the web, these fibers maintain their scattered and irregular relation to each other, which effects the production of the stronger and more regular weaving of the web of paper, as described. When the 80 flow regulator 18 is moved towards the cylinder 6, the head of the pulp in the box 4' is increased, and the stream that subsequently passes between the gage 18 and the deflector 20 enters the vat with greater force, 85 which tends to effect a more violent agitation of the pulp immediately below the ledge 18^a, and accordingly produces a clearer and more even texture of the web. Moving the strip 18 away from the drum 6 lowers the 90 head thereby increasing the volume, but reducing the agitation before the suction takes place. Paper formed by the last described adjustment usually has less tensile 95 strength laterally than when the gap between the gage and the deflector is narrowed, as explained.

By combining the feature of the flow gage 18 and the deflector 20—20^a, which 100 eliminate the streaked and uneven thickness of the paper, with the press-rolls 9, 9' and 17, and the two relatively long felts 8 and 14, which are conditioned by the suction boxes 8' and 16', the web of paper 17' is 105 delivered by the roll 17 at least 30% drier than the product of the ordinary cylinder type tissue paper machines in common use. By the adoption and use of the improvements herein shown and described, I am 110 able to run my machines at higher speed and produce clearer, finer grain, and stronger paper at comparatively low expense for machinery, power and attendance, while the final drying of the paper may be 115 effected by fewer heated driers, which require less room and steam heat and less attention and care than heretofore.

Having thus described my invention, what I claim, is—

1. In a machine for making cloudless paper, a vat, a foraminous cylinder in the vat, a flow-box separated from the vat by a submerged dam, means adjustably supported by the dam for regulating the flow of the liquid pulp over the dam, and a deflector 120 co-operating with the dam for agitating and remixing the pulp within the vat below said regulating means before the web of paper is 125 formed.

2. In a machine for making paper, the 130

combination with a vat, a foraminous cylinder in the vat, and a flow-box separated from the vat by a dam, of a gage adjustably mounted on the dam adapted for regulating the volume of the liquid pulp flowing from the flow-box to the vat, and means adjustably interposed between the gage and the cylinder and cooperating with the dam and the said gage for conditioning the pulp for forming a web of paper having substantially equal tensile strength in all directions.

3. In a machine for making cloudless tissue paper, the combination with a cylinder, a vat, and a flow-box separated from the vat by a submerged dam, of a gage mounted upon the top of the dam for regulating the flow of the liquid pulp into the vat, and a deflector disposed between the flow-box and the cylinder for preventing the pulp from contacting with the cylinder until it sinks below the gage.

4. In a machine for making paper, the combination with a vat, a foraminous cylinder rotatable in the vat, a couch-roll for driving the cylinder, and a flow-box separated from the cylinder by a dam, of means movable relatively to the dam and cylinder for regulating the volume of liquid pulp flowing from said box into said vat, and means interposed between the cylinder and the dam and cooperating with the dam and said regulating means for effecting the agitation of the pulp before it comes in contact with the surface of the cylinder.

5. In a machine for making cloudless tissue paper, the combination with a vat, a foraminous cylinder in the vat, and a flow-box separated from the vat by a submerged dam, of means for agitating the pulp within the vat before the web of paper is formed on the cylinder comprising a gage adjustably mounted on the dam and projecting into the vat, and a deflector interposed between the gage and the cylinder; said gage and said deflector being movable relatively to each other and to the cylinder for varying the extent of the agitation.

6. In a machine for making tissue paper, the combination with a cylinder, a vat, and a flow-box separated from the vat by a dam, of a gage mounted on the top of the dam and being movable towards and away from the cylinder for gaging the flow of the liquid pulp into the vat, and a deflector adjustably supported by the ends of the vat, said deflector being disposed at an angle to the gage and including a depending apron that overlaps the face of the cylinder adjacent the gage.

7. In a machine for making tissue paper, the combination with a cylinder, a couch-roll, a vat in which the cylinder rotates, and a flow-box separated from the vat by a dam, of a flow-gage mounted horizontally

on the top of the dam and being adjustable bodily towards and away from the cylinder, and an inclined deflecting bar disposed forwardly of and in a higher plane than the flow-gage and supporting a flexible apron which rides upon and shields the portion of the cylinder that faces the flow-gage.

8. In a machine for making unclouded tissue paper, the combination with a vat, a vacuum cylinder in the vat, and a flow-box separated from the vat by a dam, of a gage for varying the volume of the pulp flowing from the flow-box into the vat adjustably mounted upon the dam, means disposed between the gage and the cylinder for deflecting the pulp downwardly between the gage and the cylinder at an angle tangent to the cylinder, and means for preventing contact of the pulp with the surface of the cylinder until it sinks below the said gage.

9. In a machine for making tissue paper, the combination with a vat, a foraminous cylinder in said vat, and a flow-box separated from the vat by a dam, of means for preventing the streaking of the web of paper formed on the cylinder comprising a flow-gage supported by said dam and being movable towards and away from the cylinder in a horizontal plane, the said gage being broader than the dam and one lateral margin thereof forming a ledge that overhangs the side of the dam that faces the cylinder, a member adjustably disposed at an angle between the dam and the cylinder adapted to deflect the pulp flowing from the flow-box downwardly past the said ledge, and an apron depending from the lower margin of said member adapted to co-operate with the gage and the dam for agitating the pulp before it comes in contact with the cylinder below said apron.

10. A machine for making tissue paper, including a vat, a foraminous cylinder in the vat, a flow-box separated from the vat by a transverse dam, a couch-roll for driving the cylinder, a felt supported by and driving the said roll adapted to carry the web of paper formed by said cylinder towards the drying end of the machine means interposed between the flow-box and the vat for regulating the flow of the pulp over said dam, and means interposed between the dam and the cylinder for deflecting the inflowing pulp from the cylinder towards the dam for agitating and remixing the pulp in the vat before the web of paper is formed.

11. In a machine for making tissue paper, the combination with a cylinder, a vat, and a flow-box separated from the vat by a dam, of a slotted gage mounted upon the dam, screws passing through the slots of the gage and screwing into the dam for holding the gage in various positions rela-

tively to the cylinder, the forward margin of the gage overhanging the dam, a pulp deflecting member adjustably supported by the ends of the vat between the cylinder and the gage and parallel to said parts, and a flexible apron adapted to deflect the pulp away from the cylinder and beneath

the overhanging margin of the gage for agitating the pulp before the web of paper is formed on the cylinder.

In testimony whereof I affix my signature.

WINFIELD E. McINTYRE.
